(57) **CLAIM**

The ornamental design for an inflatable slide, as shown and described.

DESCRIPTION

FIG. 1 is a perspective view of the inflatable slide.

FIG. 2 is a left side elevational view of the inflatable slide with the right side elevational view being a mirror reflection of the left side elevational view.

FIG. 3 is a front elevational view of the inflatable slide.

FIG. 4 is a rear elevational view of the inflatable slide; and, FIG. 5 is a top plan view of the inflatable slide.
